REINFORCING PLATE FOR FENCE POSTS

Alan E. Brickman, Worcester, Mass., assignor to
The American Steel and Wire Company of New
Jersey, a corporation of New Jersey

Application September 24, 1948, Serial No. 50,909

8 Claims. (Cl. 256—47)

1

This invention relates to a post reinforcing plate and more particularly to such a plate for use with a steel fence post. Fences are ordinarily laid out in a relatively straight line so that there is a relatively small load applied to the fence post transversely of the length of the fence. However, with the development of contour farming in which the furrows are plowed according to the contour of the land so that each furrow is approximately the same elevation throughout, plowed fields in relatively hilly country are surrounded by fences which do not extend in a straight line. Instead, each fence is arranged more or less in an arcuate fashion. As the temperature changes, the wires will stretch and contract and as the wires contract they apply a transverse force to the post, which force is in addition to any other force normally thereon. To resist this force a stronger post is necessary. Thus, in making a fence in which part of the posts are arranged in a straight line and others are arranged in a curved line, it will be necessary either to use posts of different strengths or to use posts all having the strength necessary for the maximum load. The latter course is more expensive than having posts of only the required strength. It is of course desirable to use standard posts of the minimum strength necessary.

It is therefore an object of my invention to provide a reinforcing plate for use with standard fence posts which can be used to strengthen the posts when necessary.

These and other objects will be more apparent after referring to the following specification and the additional drawings in which:

Figure 1 is a perspective view of my device;

Figure 2 is an elevational view showing the reinforcing plate;

Figure 3 is a side view of Figure 2; and

Figure 4 is a horizontal section taken above the reinforcing plate.

Referring more particularly to the drawings the reference numeral 2 indicates a standard steel fence post of substantially U-shape with flanges 4 at the end of each leg of the U. The outer face 6 of the flange 4 is provided with corrugations 8 for receiving the fence wires 10. The reinforcing plate of my invention consists of a bent plate 12 having a U-shaped portion 14 with a flange portion 16 at the end of each leg of the U. Fastened to each flange 16 in a suitable manner as by welding is a plate 18 (not shown in Figure 1) which extends past the end of the leg of the U, so as to provide a groove 20. The lower part of each flange 16 is cut on a bevel

2

22 to facilitate driving of the plate into the ground. Adjacent the top portion of the plate 12 is a cut-out portion 24 which extends around the U-shaped portion thereof. A pair of lugs 26 extend into the top portion of the cut-out. When it is desired to reinforce the post, the post is driven into the ground in the usual manner and the plate 12 is slipped over the flanges 4 which fit in the grooves 20. The ground plate 12 is then driven into the ground until the bottom of the opening 24 is slightly above the ground line 28. Fence wire 10 is then placed in the corrugations 8 which are located at substantially the same level as the opening 24. The plate is then driven downwardly until it reaches the position shown in Figure 1, in which position the fence wire 10 is located in the corrugation 8 behind the lugs 26. One or both of the lugs 26 is then bent inwardly to prevent removal of the fence wire 10 and also to prevent relative vertical movement between the fence post 8 and the plate 12.

While one embodiment of my invention has been shown and described it will be apparent that other adaptations and modifications may be made without departing from the scope of the following claims.

I claim:

1. A reinforcing plate for a fence post having flanges extending in the direction of the fence with the outer face of the flanges being corrugated to receive a fence wire, said plate comprising a U-shaped portion, means cooperating with said U-shaped portion to form a groove at each end thereof for receiving the flanges of the post, said U-shaped portion having a transverse cut-out portion therein intermediate its ends said cut-out portion extending across the base and substantially into both legs of the U so that a fence wire can pass therethrough substantially parallel to said base of the U, and a lug on said U-shaped portion extending into the cut-out portion and adapted to be bent inwardly around said wire.

2. A reinforcing plate for a fence post having flanges extending in the direction of the fence with the outer face of the flanges being corrugated to receive a fence wire, said plate comprising a U-shaped portion, a plate fastened to each leg of the U-shaped portion and cooperating therewith to form a groove for receiving one flange of the post, said U-shaped portion having a transverse cut-out portion therein intermediate its ends said cut-out portion extending across the base and substantially into both legs of the U so that a fence wire can pass therethrough sub-

stantially parallel to said base of the U, and a lug on said U-shaped portion extending into the cut-out portion and adapted to be bent inwardly around said wire.

3. A reinforcing plate for a fence post having flanges extending in the direction of the fence with the outer face of the flanges being corrugated to receive a fence wire, said plate comprising a U-shaped portion, a flange portion at the end of each leg of the U, a plate fastened to each flange portion and extending toward the opposite flange portion so as to form a groove for receiving one flange of the post, said U-shaped portion having a transverse cut-out portion therein intermediate its ends said cut-out portion extending across the base and substantially into both legs of the U so that a fence wire can pass therethrough substantially parallel to said base of the U, and a lug on said U-shaped portion extending into the cut-out portion and adapted to be bent inwardly around said wire.

4. A reinforced fence post comprising a main post having flanges extending in the direction of the fence with the outer face of the flanges being corrugated to receive a fence wire, a reinforcing plate having a U-shaped portion, means cooperating with said U-shaped portion to form a groove at each end thereof for receiving the flanges of the main post, said U-shaped portion having a transverse cut-out portion therein intermediate its ends said cut-out portion extending across the base and substantially into both legs of the U so that a fence wire can pass therethrough substantially parallel to said base of the U, and a lug on said U-shaped portion extending into the cut-out portion and adapted to be bent inwardly around said wire.

5. A reinforced fence post comprising a main post having flanges extending in the direction of the fence with the outer face of the flanges being corrugated to receive a fence wire, a reinforcing plate having a U-shaped portion, a plate fastened to each leg of the U-shaped portion and cooperating therewith to form a groove for receiving one flange of the post, said U-shaped portion having a transverse cut-out portion therein intermediate its ends said cut-out portion extending across the base and substantially into both legs of the U so that a fence wire can pass therethrough substantially parallel to said base of the U, and a lug on said U-shaped portion extending into the cut-out portion and adapted to be bent inwardly around said wire.

6. A reinforced fence post comprising a main post having flanges extending in the direction of the fence with the outer face of the flanges being

corrugated to receive a fence wire, a reinforcing plate having a U-shaped portion, a flange portion at the end of each leg of the U, a plate fastened to each flange portion and extending toward the opposite flange portion so as to form a groove for receiving one flange of the post, said U-shaped portion having a transverse cut-out portion therein intermediate its ends said cut-out portion extending across the base and substantially into both legs of the U so that a fence wire can pass therethrough substantially parallel to said base of the U, and a lug on said U-shaped portion extending into the cut-out portion and adapted to be bent inwardly around said wire.

7. A reinforcing plate for a fence post having flanges extending in the direction of the fence with the outer face of the flanges being corrugated to receive a fence wire, said plate comprising a U-shaped portion, means cooperating with said U-shaped portion to form a groove at each end thereof for receiving the flanges of the post, said U-shaped portion having a transverse cut-out portion therein intermediate its ends said cut-out portion extending across the base and substantially into both legs of the U so that a fence wire can pass therethrough substantially parallel to said base of the U, and means for securing the fence wire, post and reinforcing plate together against relative vertical movement.

8. A reinforced fence post comprising a main post having flanges extending in the direction of the fence with the outer face of the flanges being corrugated to receive a fence wire, a reinforcing plate having a U-shaped portion, means cooperating with said U-shaped portion to form a groove at each end thereof for receiving the flanges of the main post, said U-shaped portion having a transverse cut-out portion therein intermediate its ends said cut-out portion extending across the base and substantially into both legs of the U so that a fence wire can pass therethrough substantially parallel to said base of the U, and means for securing the fence wire, post and reinforcing plate together against relative vertical movement.
